ROCKABLE AND WHEELABLE TOY HORSE

Henry Carl Feist, East Hampton, Conn., assignor to The N. N. Hill Brass Company, East Hampton, Conn., a corporation of Connecticut

Application September 19, 1952, Serial No. 310,459

6 Claims. (Cl. 280—1.22)

This invention relates generally to toy horses, and more particularly to toy horses of the type which children may ride.

It is an object of the present invention to provide a toy horse of this type which may not only be mounted by children of very tender age and rolled or wheeled on the floor or ground, but may be ridden by them with complete safety in imitation of the hopping gait of a real horse.

It is another object of the present invention to provide a toy horse of this type which will rock somewhat similar to a horse's gait when the child thereon merely exerts its natural efforts to wheel the toy horse on the floor or ground.

It is a further object of the present invention to provide a toy horse of this type which, in consequence of the natural efforts of a child thereon to wheel it on the floor or ground, will rock in such a fashion that the bobbing motion of the toy horse will distinctly be felt but not readily seen by the child, with the result that the child will not be frightened when riding the toy horse and will nevertheless experience thrills similar to those afforded by conventional rocking horses for which the child is far too young.

Another object of the present invention is to provide a toy horse of this type which is entirely safe for mounting by even smaller children that are as yet incapable of wheeling the toy on the floor, and which will rock slightly and harmlessly every time a child mounts the same or goes into motions that momentarily relieve or vary its weight on the toy horse.

It is a further object of the present invention to provide a toy horse of this type which, on merely being borne down or pounced upon by a child on top, will not only rock but move on the ground, so that the overall motion of the toy horse experienced by the child will be somewhat similar to the galloping gait of a real horse.

A further object of the present invention is to provide a toy horse of this type which may safely be used for still smaller children as a simple wheeler on which they may be placed by their elders and rolled about on the floor.

It is another object of the present invention to provide a toy horse of this type which, despite its rockability offers hardly any possibility to hurt or injure a child playing with it in the intended manner or even in a manner not intended or contemplated.

It is a further object of the present invention to provide a toy horse of this type of which the fore and hind legs are so spaced that they afford a stable support for the toy on the floor, and are provided with wheels by means of which the toy may be rolled on the floor, and the fore legs are rigid with the horse's body, while the hind legs are pivoted on the body and react against a well hidden compression spring to impart a slight rocking motion to the toy horse every time the same is borne down upon.

It is still another object of the present invention to

2

provide a toy horse of this type which is extremely simple in construction, yet highly attractive in appearance and performance to children of various ages, and which readily lends itself to efficient mass production at low cost.

5 Further objects and advantages will appear to those skilled in the art from the following, considered in conjunction with the accompanying drawings.

In the accompanying drawings, in which certain modes of carrying out the present invention are shown for illustrative purposes:

Fig. 1 is a side view of a toy horse embodying the present invention;

Fig. 2 is a front view of the toy horse as seen in the direction of the arrow 2 in Fig. 1;

Fig. 3 is a bottom view of the toy horse as seen in the direction of the arrow 3 in Fig. 1;

Fig. 4 is an enlarged fragmentary section through the toy horse taken substantially on the line 4—4 of Fig. 3; and

Fig. 5 is a view of the toy horse similar to Fig. 1, but showing the same in one of its different rocking positions during use.

Referring to the drawings, and more particularly to Figs. 1 to 3 thereof, the reference numeral 10 designates a toy horse having a body 12 with a head portion 14 and a tail portion 16, fore and hind legs 18 and 20, respectively, and a saddle-like seat 22. The body 12 with its head and tail portions 14 and 16 may conveniently and economically be made of a wooden board, suitably contoured to resemble the general outline of a horse's body, head and tail. The seat 22 may also be made of a wooden board, suitably contoured to resemble a saddle.

The fore legs 18 may conveniently be in the form of wooden bars which are firmly secured, as by bolts 24 and nuts 26, to the body 12 near the front end thereof. The fore legs 18 are disposed on opposite sides of the body 12 and form a frame of inverted V-shape (Fig. 2) for the support of the front of the horse's body on the floor or ground. The fore legs 18 are, in this instance, provided with wheels 28 which may be carried by the ends of an axle 30, suitably journalled in the lower ends of the fore legs. The fore legs may depend from the horse's body 12 in any suitable disposition, and they are in this instance slightly inclined forwardly.

The hind legs 20, which may also be in the form of wooden bars, are pivotally connected, by bolt means 32, for instance, with the horse's body 12, and form a frame of inverted V-shape similarly as the fore legs 18. The hind legs 20, which are also disposed on opposite sides of the horse's body 12, are intermediate their ends reinforced by a cross-tie 34 which in this instance is a wooden spacer firmly clamped to the hind legs by bolt and nut means 36. The hind legs 20 are provided with wheels 38 which may be carried by the ends of an axle 40, suitably journalled in the lower ends of the hind legs.

55 The pivotally suspended hind legs 20 on the horse's body are adapted to impart a rocking motion to the toy horse when a child mounted thereon rides the horse. To this end, a compression-type spring 42 urges the hind legs 20 into the normal position shown in Fig. 1, in which the spacer 34 between these legs bears against a belly-like contour portion 44 of the horse's body. The spacer 34 and the tail portion 16 of the horse's body are provided with substantially aligned sockets 46 and 48, respectively, in which the opposite ends of the compression spring may conveniently be seated (see particularly Fig. 4).

It will be noted from Fig. 1 that the hind legs 20 are in their normal position inclined rearwardly and downwardly relatively steeply to the floor or ground on which the toy horse stands. Accordingly, a child mounting the toy horse and bearing down on it as shown in Fig. 5,

will cause the hind legs 20 to swing about their pivot support 32 into a position of less steep inclination to the floor or ground, against the tendency of the spring 42 to return the hind legs to their normal position. The aforementioned swing of the hind legs 20 into a position of less steep inclination to the floor or ground will result in a corresponding lowering of the rear of the toy horse, imparting thereby to the child the sensation of a rocking horse. When the child in its natural effort of merely wheeling the toy horse on the floor or ground repeatedly bears down on and partially lifts its weight from the seat 22, the rolling or wheeling motion of the toy horse is accompanied by repeated rocking motions, much to the delight and amusement of the child.

The instant toy is noteworthy in that it is not only harmless to play with, but will have distinct appeal and fascination for youngsters of considerably varying ages. Thus, the instant toy horse serves admirably as a carriage on which a child of even very tender age may be placed and wheeled on the floor or ground by an attendant. As the child grows a little older, it may safely be left alone with the toy horse, and the child will soon find out that a rocking sensation is in store when mounting the horse and endeavoring to wheel the same. Before long the child will know that the rocking sensation experienced when riding on the toy horse is caused and controlled by the movement of its own body, and the child may then rock the horse or wheel the same, or both, at its own election.

The instant toy is particularly safe as a rocking horse for youngsters of relatively tender ages which would ordinarily not be permitted to play with toy horses on conventional rockers. Thus, by tiltably mounting the hind legs of the instant toy horse on the horse's body and having the fore legs rigid therewith, a child mounted on the toy horse will fully experience or feel the rocking motion of the horse, but will see only the slight bobbing motion of the horse's head in front, with the result that the child will not lose its sense of balance and topple from the horse, which it probably would if it could observe the rocking motion of the horse's rear. By the same token, even timid children that are easily frightened may safely ride the instant toy horse because they cannot possibly see anything alarming in the slight bobbing motion of the horse's head, yet may experience the thrills of a rocking horse. In order that a child may experience substantially the full rocking motion of the toy horse, the seat 22 is preferably located in relatively close proximity to the hind legs 20 and remote from the fore legs 18.

Added to the thrill of experiencing a rocking motion with each downward thrust on the horse's seat is a slight wheeling motion of the toy horse on the floor or ground, so that the action of the instant toy horse approaches even closer the action of toy horses on conventional rockers without, however, offering any of the hazards of the latter. Thus, forceful rearward rolling displacement of the hind legs 20 on each rocking motion of the toy horse will in most instances bring about a slight wheeling motion of the fore legs 18 and, consequently, a wheeling motion of the entire toy horse, so that a child riding on the horse will experience an overall motion which is somewhat similar to the galloping gait of a real horse.

The instant toy horse may, if desired, be devoid of any function as a wheeler by simply omitting the wheels on the fore legs 18 and having the latter rest directly on the floor or ground. Such a toy horse would be especially safe for use as a rocker by children of very tender age. It is also fully within the scope of the present invention to have the fore legs tiltably mounted on the horse's body and the hind legs rigid thereon, although the hereinbefore described and illustrated form of the toy horse is greatly preferred for reasons of maximum enjoyment and safety in use of the toy horse.

The safe use and enjoyment of the instant toy horse is even enhanced by the specific location and mounting of the compression spring 42. Thus, the spring 42 is rela-

tively hidden and hardly accessible to a child riding the toy horse, and the ends of the spring are safely anchored out of reach of a child following its natural instinct of investigating the mechanism of the toy.

5 The instant toy horse is exceedingly simple and rugged in construction, yet highly fascinating in its action and safe in use, and readily lends itself to efficient mass production at very low cost. The instant toy horse may also be embellished to resemble a horse rather closely. This 10 may readily be accomplished by providing the various parts of the toy horse with appropriate designs, such as the design D on the opposite sides of the head portion 14 of the horse's body.

The invention may be carried out in other specific ways 15 than those herein set forth without departing from the spirit and essential characteristics of the invention, and the present embodiments are, therefore, to be considered in all respects as illustrative and not restrictive, and all changes coming within the meaning and equivalency range 20 of the appended claims are intended to be embraced therein.

What is claimed is:

1. A rocking horse, comprising a flat board of an outline resembling a horse's body, and of such uniform 25 thickness as to give no indication of a horse's body when viewed edgewise; a horse's imitation head at the front of said body board; a saddle-like seat on top of said body board; front leg means rigid with and depending from the front of said body board; a pair of rear legs coaxially 30 pivotally suspended with their upper ends from the opposite sides of said body board, said rear legs being formed of wooden bars cut away at their upper ends to provide flats which bear against said body board and are so inclined to the longitudinal axes of their respective rear legs 35 35 that the latter diverge outwardly from said body board; a spacer between and secured to said rear legs and extending underneath said body board, said spacer and rear legs forming a rigid frame; and a compression-type spring interposed between said body board and spacer and normally urging said frame into a position in which the same 40 is inclined relatively steeply to the floor or ground rearwardly and downwardly from said body board and said spacer is in stopping engagement with the bottom edge of said body board, said spring yielding to permit rocking of said frame into less steep inclination to the floor or 45 ground on bearing down on said body board.

2. A rocking horse as set forth in claim 1, in which the flats on said rear legs extend beneath said body board, and said spacer is interposed between said flats.

3. A rocking horse as set forth in claim 1, in which 50 said body board has an integral downward extension of the same uniform thickness as and coplanar with said body board and having an outline resembling a horse's tail, said tail extension having a recess in its edge, and said spring being seated with one end in said recess and 55 bearing with its other end against said spacer.

4. A toy horse, comprising a flat board of an outline resembling a horse's body; a horse's imitation head on the front of said body board; first leg means rigid with and depending from adjacent the front of said body board 60 for supporting the same on the floor or ground; a frame of inverted V-shape having diverging legs and being pivotally suspended at the top from said body board intermediate the front and rear of the latter with said diverging legs being disposed on opposite sides of said 65 body board, and said body board having a stop surface adapted to be engaged by said frame in its normal position of relatively steep inclination to the floor or ground rearwardly of and downwardly from said body board; a compression-type spring interposed between said frame and body board, said spring normally urging said frame 70 against said stop surface and yielding to permit rocking of said frame into less steep inclination to the floor or ground on bearing down on said body board; and a saddle-like seat on the top of said body board and spaced from

said head, said seat extending to both sides of said body board and being vertically above the pivot suspension of said frame.

5. A toy horse as set forth in claim 4, in which the center of said seat is substantially vertically above the pivot suspension of said frame.

6. A rocking horse comprising a flat board of an outline resembling a horse's body; a horse's imitation head at the front of said body board; leg means rigid with and depending from adjacent the front of said body board for supporting the same on the floor or ground; a frame of inverted V-shape having a pair of diverging legs and being pivotally suspended at the top from said body board intermediate the front and rear of the latter, said diverging legs being disposed on opposite sides of 15 said body board and said frame being normally disposed at relatively steep inclination to the floor or ground rearwardly of and downwardly from said body board; spring means operatively connecting said body board and frame and yielding to permit rocking of the latter into less 20

steep inclination to the floor or ground on bearing down on said body board; and a saddle-like seat on the top of said body board vertically above the pivot suspension of said frame and spaced from said head so that an unseatable length of the top edge of said body board extends between said seat and head.
